UNITED STATES PATENT OFFICE.

HERBERT ALFRED LUCAS BARRY, OF LONDON, ENGLAND, ASSIGNOR TO SILVER LOCK STITCH SEWING MACHINE SYNDICATE LIMITED, OF BLOOMSBURY, LONDON, ENGLAND, A BRITISH LIMITED LIABILITY COMPANY.

LOCK-STITCH SEWING-MACHINE.

1,380,630.

Specification of Letters Patent. Patented June 7, 1921.

Application filed December 11, 1920. Serial No. 430,007.

To all whom it may concern:

Be it known that I, HERBERT ALFRED LUCAS BARRY, a subject of the King of Great Britain and Ireland, residing at 46 St.

5 Marys Mansions, Paddington, London, England, have invented new and useful Improvements in and Relating to Lock-Stitch Sewing-Machines, of which the following is a specification.

10 This invention relates to improvements in lock stitch sewing machines and has for its object the provision of means whereby high efficiency, low prime cost, light weight, simplicity of construction and small upkeep 15 and repair charges are obtained.

The invention consists in the arrangement and association of particular mechanism adapted to produce lock stitch sewing upon operation.

20 In order that the invention may be the better understood I will now proceed to describe the same in relation to the accompanying drawings, reference being had to the figures and numerals marked thereon.

25 Like numerals refer to like parts in the various figures in which:

Figure 1 illustrates a side elevation of a machine constructed in accordance with the invention.

30 Fig. 2 is an end elevation of the machine illustrated in Fig. 1.

Fig. 3 is a plan view of the machine illustrated in Fig. 1, the upper projecting arm and the work table being removed to exhibit 35 the parts normally concealed thereby.

Fig. 4 is a detail of the presser foot lever.

Fig. 5 is a side elevation of the detail illustrated in Fig. 4.

Fig. 6 is a detail of the needle thread re- 40 lease.

In the drawings the main frame 1 of the machine is formed with an arm 2, a box 3 for the needle bar actuating gear, a box 4 for the driving gear and a bed plate 5. A 45 fly wheel 6, adapted to be rotated in known manner drives a spur wheel 7 through the intercession of a spring pressed coupling pin 8. The spur wheel 7 engages two pinions 9 and 10; the pinion 9, through the shaft 11, disk 12, pin 13, and cam slot device 14, operating the needle bar 15, and thread

feed 16, while the pinion 10 through the shaft 17, eccentric 18 and lever 19 moves the shuttle carriage 20 and operates the feed 21.

The lever 19, operated by the shaft 17, has two plane contact surfaces 22 disposed parallel to one another and mounted on one end thereof, the shuttle carriage 20 being mounted on the opposite end.

The eccentric 18 has a spherical surface which is disposed between the parallel plane contact surfaces 22 of the lever 19, said eccentric 18 oscillating the said lever 19 about its pivot 49 when rotated. The pivot 49 is 65 mounted in a boss 50 which is formed integral with the base plate 5 or is attached thereto in well known manner. The shuttle carriage 20 disposed on the end of the lever 19 carries the shuttle 23 of known construction and moves in an arc of a circle the center of which is coincident with the center of movement of the lever 19. This arc of movement is so disposed relative to the operative axis of the needle bar 15 that upon 70 operation in proper sequence of the needle 24 and shuttle 23 with their attendant threads, stitches having lock stitch characteristics are produced.

To enable the material being sewn to be 80 automatically fed to the needle 24 a presser foot 25 operating under control of the spring 26 is provided in proximity to the needle 24 and causes the material being sewn to be engaged by the teeth 21^a of the feed 85 21 in known manner. The feed 21 is operated by two cams 27 and 28 which are mounted on the shaft 17; the cam 27 being adapted to lift the feed member 21 into contact with the presser foot 25 and engage 90 the material with the teeth 21^a while the cam 28 is adapted to move the feed member 21 forward while in the raised position and allow it to move backward under the tension of the spring 29 while in the lowered position.

To vary the length of stitch, the backward travel of the feed member 21 is more or less limited as desired by means of the stop 30 having a finger knob 31.

The tension on the needle thread is adjusted by means of a finger knob 40 which

is adapted to vary the stress in the spring 41 and consequently the effective friction between the spring operated plates 37 and 38 between which the thread passes on its 5 way from the reel 39 to the feed 16.

In association with the plates 37 and 38 is a plate 42 having a tail piece 43 adapted to be engaged by a cam 44 formed in the finger lever 45.

10 The lever 45 is pivoted at 46 and has a cam like projection 47 adapted to engage the radially extending member 48 mounted on the rod 49' of the presser foot 25. When the finger lever 45 is raised from 15 the position illustrated in Fig. 2 the part 48 is engaged by the projection 47 and raised, thereby releasing the pressure of the foot 25 on the teeth 21^a of the feed member 21 and simultaneously the end of the 20 tail piece 43 is engaged by the cam 44 which releases the needle thread.

The tension on the shuttle thread is adjusted in known manner and calls for no specific explanation.

25 In proximity to the fly wheel 6 a spool winding device 32 is disposed, the friction wheel 33 thereof being adapted to be moved into engagement with the periphery of the fly wheel 6. To enable this to be readily 30 effected the device 32 is pivoted at 34, a clamping screw 35 being provided so that the periphery of the friction wheel 33 may be maintained in contact with the periphery of the fly wheel 6 for spool winding 35 and out of contact when normal operation of the machine is required.

During the spool winding operation the spring pressed coupling pin 8 transmitting motion from the fly wheel 6 to the spur 40 wheel 7 is disengaged thereby obviating

needless operation of the needle bar 15 and shuttle carriage 20.

It will be seen that by the construction outlined the work table 51 has no moving parts mounted thereon or attached thereto 45 thus enabling the machine to be readily assembled and timed without the work table 51 being in position.

When not in use a cover may be employed to protect the machine from dirt 50 and damage, said cover being maintained in position by means of suitable latches which may engage projections such as 36. To enable the size of the cover to be reduced to a minimum the handle 6^a of the 55 fly wheel 6 may be removed when the cover is to be employed.

I claim:—

In a sewing machine having a head carrying a presser foot bar and a lever for lifting the same, a thread tension comprising a stud projection from said head, a pair of tension disks loosely mounted on the stud, a spring on said stud forcing one of said disks toward the other, a plate on 65 said stud interposed between the outer disk and the spring and having a tail piece extending from one edge of the plate at right angles thereto to project into the path of the lever, and a cam surface on said lever 70 engageable with the tail piece to move the plate against the action of the spring and thereby release the pressure on the plates.

In testimony whereof I have signed my name to this specification in the presence of 75 two subscribing witnesses.

HERBERT ALFRED LUCAS BARRY.
